UNITED STATES PATENT OFFICE.

HERMAN SACKS, OF CHICAGO, ILLINOIS.

BLOOMERS.

1,425,795.

Specification of Letters Patent. Patented Aug. 15, 1922.

Application filed January 3, 1922. Serial No. 526,515.

To all whom it may concern:

Be it known that I, HERMAN SACKS, a citizen of the United States, residing at Chicago, in the county of Cook and State 5 of Illinois, have invented certain new and useful Improvements in Bloomers, of which the following is a specification.

My invention relates to bloomers and particularly of the type ladies wear in gymnasium and athletic uses having a waistband composed of elastic and inelastic portions and has for its principal object the provision of a garment which is properly balanced, that is with sufficient material at the 10 front and rear of the garment to fit snugly and properly upon the wearer, and with the material making up the garment distributed in such manner that all bulkiness is overcome and held in permanent position at the 15 front of the garment by plaiting, Shirring, or gathering,

Another and further object of my invention is the provision of a bloomer properly made from a hygienic standpoint in that it 20 is supported from the hips of the wearer with a minimum amount of pressure at the front of the garment with a smooth waistband across the abdomen of the wearer instead of the usual elastic waistband extending 25 entirely around the body of the wearer as has been common heretofore.

Another and further object of my invention is the provision of a garment which 30 will remain in proper position about the body of the wearer during gymnasium work, athletic contests and the like without twisting or turning sidewise about the body of the wearer and thus interfering with the freedom of movement of the wearer.

Another and further object of my invention is the provision of a garment which is 35 adapted to fit properly within a certain range of sizes and thus a necessity for garments of many different sizes is overcome.

Another and further object of my invention is the provision of a bloomer which is 40 simple in construction which can be easily manufactured at a minimum cost and which provides a bloomer which fits snugly about 45 the body of the wearer so that if desired skirts and other garments may be worn over the bloomers and there are no heavy folds in the bloomers and the outer garment is allowed to fit smoothly over the bloomer.

These and other objects of my invention 50 will be more fully and better understood by

reference to accompanying set of drawing which is a front elevational view of my improved bloomer.

Referring now specifically to the drawing 60 and in which like reference characters refer to like parts throughout, a garment is shown comprising leg portions 10 and 11 provided with Shirred portions 12 at the bottoms thereof within which elastic is inserted, and 65 a trunk portion 13 having secured thereto at its upper edge a waist band composed of an elastic portion 14 and an inelastic portion 15, the said elastic portion being secured to the ends of the inelastic member 15 by 70 stitching or by any approved manner. The elastic portion 14 is formed by gathering or Shirring the garment at its upper edge within which an elastic member is placed which is secured to the ends of the inelastic 75 portion 15.

A central lap seam 16 is provided by means of which the body portion of the garment is secured together the said seam extending around the crotch of the garment 80 and up to the waistband at the rear. Extending vertically near the front side-portions of the garment and at each side therefrom is a pair of short plaits 18 and 19 which are sewed down tightly at their upper 85 ends to the inelastic portion 15 of the waist band but are not sewed for any other portion of their length so as to allow expansion of the body of the garment to accommodate 90 itself to the body of the wearer. Extending down the front of the garment is a couple of wide plaits 20 and 21 also sewed down tightly at their upper ends to the inelastic waist band 15, but free for the balance of 95 their length below the waist band. A pair of plaits 22 and 23 are also provided which are positioned the intermediate plaits 20 and 21, and the side plaits 18 and 19, these plaits also being sewed down tightly at their upper ends to the inelastic portion of the 100 waistband 15.

It will thus be noted that the plaits at the front of the garment are all secured at their upper ends to the inelastic portion 15 of the waistband so that all expansion of the 105 garment in the body portion is provided for in the plaits below the waist line, although the garment may be Shirred or gathered at the front instead of plaited and the same result accomplished, although I prefer to 110 employ plaits because the garment remains more smooth than if gathered or Shirred.

The garment is held in proper position about the waist of the wearer by the elastic portion 14 of the waist band without any appreciable pressure upon the wearer by the 5 inelastic portion of the waistband. Furthermore, by providing a waistband whose rear portion is elastic and providing plaits at the front of the garment, I am able to provide a garment which can be used for a 10 larger variety of figures than the usual bloomer and which will also fit snugly about a smaller figure, the range of sizes being very much greater than what has been possible heretofore and I am able to accomplish 15 the desired objects of my invention as set forth above.

While I have described more or less precisely the details of construction, I do not wish to be understood as limiting myself 20 thereto, as I contemplate changes in form

and proportion of parts and the substitution of equivalents as circumstances may suggest or render expedient without departing from the spirit of my invention.

I claim:

25

As a new article of manufacture bloomers comprising leg portions, and a trunk portion having vertically extending plaits at the front thereof and waist band composed of an inelastic portion at the front and an 30 elastic portion at the rear of the garment, the said plaits being permanently and in-expansively secured to the inelastic portions of the waist band at their upper ends, and having their lapped portions free and ex- 35 pansible below the waist band.

Signed at Chicago, Illinois, this 21st day of December, 1921.

HERMAN SACKS.
